UNITED STATES PATENT OFFICE.

ERNEST H. THOMPSON, OF CAMBRIDGE, MASSACHUSETTS.

FARE-BOX.

1,364,156.

Specification of Letters Patent.

Patented Jan. 4, 1921.

Application filed December 4, 1916. Serial No. 134,864.

To all whom it may concern:

Be it known that I, ERNEST H. THOMPSON, a citizen of the United States, and resident of Cambridge, Massachusetts, have invented 5 certain new and useful Improvements in Fare-Boxes, of which the following is a specification.

This invention relates to fare boxes of the type used at pay-as-you-enter stations, or in 10 street cars, and is intended to provide a device of this kind which shall be simple and reliable in its operation, and shall be completely adequate to the practical requirements demanded by such service.

15 The fare box shown is of the automatic type. That is, the coin, after being deposited, causes various operations of mechanism by which certain selecting coin-depositing or excluding devices are brought into play to 20 secure the deposit in the proper receptacle, of a genuine coin of the appropriate denomination, or to exclude slugs or coins not conforming to the standard size and thickness of the coins for which the device is intended.

25 Among the features characterizing the present invention, is the provision by which the deposited coin is temporarily held exposed to inspection before it is carried away 30 by the automatic coin-transferring device to its appropriate receptacle.

Another feature of the invention consists 35 in the employment of a preliminary automatically operated selecting device for transferring the coin from the outer receptacle in which it may be inspected, to the selecting-coin-depositing mechanism, so that only one coin at a time can be fed to the coin-depositing devices.

40 Another feature of the invention consists in a mechanism for causing the actuation of the preliminary selecting slide in order to remove the preceding coin from the inspection compartment to the coin-depositing and 45 selecting devices. By the arrangement employed any number of coins may be thrown simultaneously into the coin hopper from which they will be fed one by one to the coin-transferring and registering mechanism, by the automatic operation of the machine, the value of each coin being registered or indicated as it is passed to its appropriate 50 receptacle. The invention also consists in the construction and arrangement of various 55 safety devices to permit the elimination of false coins or slugs, and to prevent any in-

jury to the working mechanism by the introduction of such false coins, slugs or buttons.

In the embodiment of the invention illustrated in the accompanying drawings, the 60 mechanism employed for handling the coin, is electrically actuated by means of an electric current, which is controlled by the coins actually deposited. The fare box is constructed with a view to containing within 65 the same casing, an automatic change delivering mechanism, but such change mechanism is not shown in detail herein, but will be made the subject matter of another application.

70 These and other features of the invention will be particularly explained hereinafter and will be defined in the claims hereto annexed.

In the accompanying drawings I have 75 illustrated the preferred mode of embodying the principles of this invention in which—

Figure 1 is a vertical section showing the coin-receiving hopper in its relation to the automatic coin-transferring and selecting 80 devices.

Fig. 2 is a side elevation showing the connection between the actuating plunger of solenoid, and the coin selecting and transferring mechanism partly broken away.

85 Fig. 3 is a detail view in horizontal cross section showing the electrical connection in the preliminary circuit closing device below the hopper on plane 3—3 of Fig. 8.

Fig. 4 is a detail view in elevation showing the toggle connection between the actuating rock shaft and the coin selecting and depositing mechanism operated thereby.

90 Figs. 5, 6 and 7 are detail views of the mechanism by which the appropriate movement of the coin register is secured, to register various denominations of coin.

Fig. 8 is a front elevation of the complete 95 assembled device showing the coin stacks into which the nickels and dimes are distributed, and from which they may be drawn by the change maker device.

100 Fig. 9 is a view of the removable top receptacle carrying the receiving hopper taken at right angles to the plane of Fig. 8.

Fig. 10 is a detail view in elevation showing the selective ledges forming the terminals of the various electric circuits for coins of different denominations.

110 Fig. 11 is a detail view of the preliminary circuit-closing device below the hopper.

Fig. 12 is a rear elevation illustrating par-

ticularly the solenoid plunger construction and the trains of gearing for operating the fare register.

Fig. 13 is an enlarged detail view illustrating the circuit closing switch for controlling the solenoid circuit.

Fig. 14 is a side elevation showing a part of the individual trains of mechanism for actuating the fare register according to the 10 denomination of the individual coin.

Fig. 15 is a detail view in elevation showing the lock for preventing disturbance of the pinion that actuates the fare register.

Figs. 16 and 17 are detail views in planes 15 at right angles to each other illustrating the retarding mechanism controlling the movement of the coin-depositing devices.

Fig. 18 is a plan of the automatic coin selecting slide beneath the hopper.

20 Figs. 19, 20 and 21 are detail views showing the runways or passages for conducting the various coins to their appropriate receptacles or containers.

Fig. 22 is a diagrammatic view illustrating the different electric circuits employed 25 in the device.

Before describing the detailed construction of the parts I will briefly explain the general nature of the operations performed 30 by this apparatus.

It is the intention that the public paying fares shall drop their coins into the top of an open hopper, which in this case is formed with a perforated spider, the openings of 35 which are of a size to admit nickels dimes and pennies, and to exclude larger coins. The coin falling through the apertures in the spider drops upon two opposed ledges or supports which form the separated terminals 40 of the electric circuit of a relay magnet, which magnet acts to close the switch in the solenoid circuit for the purpose of actuating the solenoid plunger, which in turn, by suitable mechanical connections, actuates the 45 coin-selecting depositing and registering mechanism. One of these terminals is pivoted and has mechanical connection with the automatically operated coin-transferring mechanism, to move it out of the path of 50 the coin resting upon it, thereby allowing the coin to drop into an open funnel onto a coin-transferring slide where the coin remains exposed to inspection through the glass sides of the top of the fare box, until 55 the next following coin again closes the circuit between said electric terminals to cause the movement of the solenoid plunger, and the consequent actuation of the coin-transferring and selecting mechanism.

60 The aforesaid slide delivers the coin into a runway which has selective passages to receive nickels, dimes or pennies, and guide them to their respective supporting ledges in a vertical chute opposite the transferring plunger. From this point, the transferring

mechanism passes the coin on toward its appropriate coin stack or container where it comes to rest, and at the same time the coin is registered on the coin register according to the value of each individual coin. It will 70 be understood that the slide aforesaid, serves a two-fold function; namely, to exclude articles like buttons that can pass through the spider in the top of the coin box, but is too thick to be transferred by the slide, and also 75 to permit the inspection of the coin before it is transferred to the interior of the machine, and to insure the transfer of a single coin only at a time.

In the practice of the invention according 80 to the mechanism illustrated in the drawings, I provide a suitable vertical casing having a removable top casing *a* in the upper open end of which is a perforated spider *a'* capable of admitting, in this case, nickels, 85 dimes and pennies into the vertical chute or passage *a''*, said passage being of narrow cross section to compel the coin to fall in vertical position onto the supporting terminals or plates *b*, *b'*, arranged in opposition 90 to each other, and insulated as shown in Fig. 3. The supporting plate *b'* is mounted on a rock shaft *b''* (Fig. 11) which is normally held by a tension spring *b'''* so as to cause the plate *b'* to project partly across the 95 passage *a''* to obstruct the passage of the coin.

The coin by its contact with parts *b*, *b'*, closes the circuit in the relay magnet *x*, as indicated in Fig. 22, which actuates switch 100 *y'* of the solenoid circuit *y* to actuate the solenoid plunger *y''*. The solenoid plunger is held in normally raised position by a coil spring *y'''* mounted in the surrounding casing *y''* for the purpose of actuating the coin- 105 transferring and registering mechanism.

The coin-transferring and selective mechanism embraces essentially, two vertical bars or cross heads, *c*, *c'* united at top and bottom by tie-rods *c''*. The front bar *c'* 110 of the cross head frame carries three vertically aligned horizontal plungers *c³*, *c⁴*, *c⁵*, which pass through small apertures in a partition wall *a¹⁰* of the casing. Another wall *a²⁰* of the casing carries three vertically 115 aligned fixed bearing sleeves *d*', *d''*, *d'''*, forming horizontal bearing sockets for a vertical series of plungers *c⁶*, *c⁷*, *c⁸*, which are arranged in alignment with the forward plungers *c³*, *c⁴*, *c⁵*. These plungers *c⁶*, *c⁷*, *c⁸*, have 120 no positive connection with any actuating mechanism, but are pushed rearwardly by the forward plungers *c³*, *c⁴*, *c⁵*, respectively, acting through the medium of an interposed coin. They are also centrally bored to allow 125 the plungers *c³*, *c⁴*, *c⁵*, to telescope into them without causing them to slide back when there is no coin interposed between their forward ends and the rear ends of their co-operating plungers, *c⁶*, *c⁷*, *c⁸*, respectively. 130

The coin falling from the slide member d in a manner hereinafter to be described, drops into the vertical passage behind the wall a^{10} , and is kept in an upright position by the diaphragm or partition a^{12} , which has large apertures concentric with the axes of the respective plungers to freely admit the passage of a coin laterally through said partition. Between said partition a^{12} and the wall a^{10} , as best shown in Fig. 10, are placed three vertically arranged sets of ledges e , e' , and e^2 , mounted upon plates of insulation e^3 , e^4 , and electrically connected with the relay magnet x to form the separated terminals of the circuit embracing said electro-magnet. The upper pair of ledges are spaced apart the proper distance to allow a penny or a dime to fall between them while retaining a nickel. The ledges e' are spaced apart sufficiently to allow a dime to pass between them, but to retain a penny, while the ledges e^2 are positioned to retain a dime.

A nickel falling into the vertical coin chute comes to rest upon the ledges e thereby closing the circuit of the electro-magnet, energizing the same and closing the switch y' to energize the solenoid circuit y , thus pulling down or depressing the solenoid plunger y^2 , which is slotted as shown in Figs. 2 and 12, to receive a forked lever or arm f which engages the cross pin g^6 , located in said slot by which said arm or lever is pulled down by the downward movement of the plunger, and is swung upward by the return movement of the plunger, which return movement is effected by the spiral compression spring y^8 , when the solenoid circuit is broken.

This actuating arm f is operatively secured to a rock shaft f' by a strong clutch connection for the purpose of allowing this connection to yield to permit the descent of the solenoid plunger y^2 , in the usual manner in case there is any obstruction to the normal operation of the coin-transferring mechanism due to the presence of a slug or button of such size as to block temporarily the movement of the coin-transferring mechanism. This clutch connection as shown in Fig. 2, is effected by means of one or more pawls f^2 , pivotally mounted on the lower or forward end of the arm f and normally spring pressed into engagement with notches in a disk f^3 secured to the rock shaft f' . The engagement of the pawl with its notch is sufficiently strong to operate the rock shaft and the coin-transferring mechanism under normal conditions, while allowing the pawl to ride out of its engaging notch in the disk f^3 to allow the lever f to rotate on the shaft f' without rotating the shaft.

The main cross head is operatively connected from the rearward bar c to the rock

shaft by means of a pair of toggle levers g , g' , the former being secured to the rock shaft while the latter is pivotally connected with the bar c so that the clock-wise rotation (Figs. 2 and 4) of the rock shaft f' acts to extend the toggle lever connection and force the cross head carrying the plungers c^3 , c^4 , c^5 , rearwardly.

If there is any coin interposed between the rear end of either of the three plungers mentioned, it is pressed bodily to the rear against the forward face of the corresponding plunger c^6 , c^7 or c^8 , as the case may be so that the coin is carried through the funnel-shaped aperture through which said idler plungers c^6 , c^7 or c^8 slide. These funnel-shaped aperture h , h' and h^2 , are of a diameter to barely permit the appropriate coin to pass through into the chute or runway behind said aperture. Each of these idler plungers is provided with a rearwardly projecting stem c^{10} which abuts against the front end of an adjustable set screw c^{12} , secured adjustably in the bar c of the cross head in line with the respective extension stems c^{10} of the various idler plungers, so that on the return or forward movement of the cross heads, these abutting screws push against the idler plungers to restore them to their normal forward position, as shown in Fig. 1. As will be seen, there is a slight lost motion or clearance between the two sets of plungers in excess of the thickness of the coin so that on the return movement the plungers c^3 , c^4 , c^5 are advanced a short distance before the thrust pins or screws c^{12} impinge against the rearwardly extending stems c^{10} . The object of this clearance or lost motion, is to release the respective coins from the pressure between the two co-operating sets of plungers in order that they may fall freely into the chute or passage i . The interior of said chute i is provided with inclined ribs i' , i^2 and i^3 , forming runways or passages to allow the respective coins to roll or pass into their respective stacks or containers i^4 , i^5 , i^6 , so that the nickels, dimes and pennies are sorted out or distributed to their appropriate containers from which they may be removed by the automatic change maker for the purpose of delivering change. The passage or runway to each coin stack or receptacle is provided with an overflow aperture i^7 , i^8 , i^9 which allows the respective coins to fall to the bottom outside of said containers, but of course inside the outer casing.

To prevent the too rapid movement at the initial part of the return stroke of the solenoid plunger when the circuit is broken, which might result in again gripping the coin between the edge of the opening and the plungers before it has dropped clear below them, I employ a retarding device or ratchet

mechanism which checks the initial upward movement of the plunger, while allowing it gradually to accelerate. To this end, as shown in Figs. 2, 16 and 17 the downwardly extending end or side of the lever f is constructed in the form of a sector gear f^{20} intermeshing with a pinion m on an arbor m' , on which is mounted a disk m^2 yieldingly attached to the arbor by means of a coil or 10 take up spring m^3 , which disk carries a pawl m^4 coöperating with a ratchet wheel m^5 that is compounded with a spur gear or pinion m^6 , that is loose on the arbor m' . Through a train of gears or pinions m^7 , m^8 , 15 m^9 , the rotation of the pinion m^6 is transmitted to the counter-shaft m^{10} on which is a heavy drum m^{11} . The ratchet is so arranged as to ride over the ratchet wheel without positive engagement during the 20 downward movement of the plunger, but to engage the ratchet wheel on the return movement of the plunger, and set the retarding mechanism into operation. This arrangement gives the desired initial retardation or check to the upward movement of the plunger, while allowing that upward movement to accelerate in order to shorten the period of its traverse, and at the same time avoids the transmission of 25 sudden shock to the speed mechanism.

The coin-removing slide d , arranged at the bottom of the hopper or upper receptacle, is operatively connected with the bar c' of the cross head, by means of an upwardly extending arm o , whose upper end lies in the plane of movement of the slide d , so as to push the slide rearwardly during the rearward movement of the cross head. The slide is returned to normal position by 40 a connecting spring o' , one end of which is secured to the arm o , and the other end of which is attached to a pin on the bottom of the slide d , the object being to allow the cross head to return to normal position even if the slide be obstructed against return. The slide d is mounted in a horizontal runway or bearing plate o^3 having an aperture o^4 registering with the open bottom of the hopper o^5 . The slide d has a similar aperture d^{20} adapted to register with this opening o^4 when the slide is in its rearmost position, but normally locked while in advance of said opening. The slide should not exceed in thickness the thickness of a nickel, 55 which is the largest coin to be fed into the machine according to the present design. Consequently if any small object, such as a button is dropped into the hopper, it will on account of its extra thickness, block or 60 prevent the normal movement of the slide without breaking any parts or interfering with the normal movement of the cross head.

For the purpose of removing such a foreign article blocking the slide, I provide

in the the bottom of the runway o^8 , a hinged trap door o^{10} normally held in closed position against the end face of the slide by means of a torsion spring o^{11} . The hinge of the door has a projecting finger o^{12} adapted to be engaged by a push rod o^{13} that can be operated from the outside of the machine to open the trap door and allow the button or other article to drop down outside of the coin-chute so as not to record on the register thereby clearing the slide for the performance of its normal functions.

The means for dropping the pivoted contact plate b' to allow the coin to fall in the hopper, is best shown in Figs. 1, 8, 9 and 11. On the slide d as shown in Fig. 1 is located a pin or lug b^6 adapted to engage the downwardly extending arm of an angle lever b^7 whose horizontal branch engages a vertical slide rod b^8 arranged to thrust upward against the arm b^9 on the rock-shaft b^{10} which carries a crank arm b^{11} having a projecting pin b^{12} of insulating material adapted to engage a protecting arm b^{13} of the separate shaft b^2 so as to move the pivoted coin retaining member b' against the tension of the spring b^3 to allow the coin to drop, while permitting the member b' to resume its normal position when the actuating rod b^8 drops. The pin b^6 is located so as to act during the latter part of the coin transferring stroke of the cross head, so that before the coin retained by the member b' has time to fall to the bottom of the hopper, the slide d will have returned to normal position thereby leaving the fallen coin at rest on top of the slide d . It will be noticed that the slide d removes the coin from the hopper on the return or forward stroke of the cross-head, and that on its initial or rearward stroke it moves in position to receive the coin within its recess preliminary to removal thereof.

It is desirable that the automatically operated fare box shall register the value of the coins deposited. To this end I have attached a rotary counter or register which as indicated in Fig. 12, may be of any suitable or appropriate construction forming no part of the present invention, but which is designed to register from the right, each step or number on the righthand wheel or disk thereof, indicating one penny, the periphery of the wheel being graduated into ten consecutively numbered sub-divisions, so that the rotation thereof by a single step, indicates one penny on the register, the rotation thereof five steps, indicates five pennies, or a nickel, and the complete rotation thereof, indicates or counts a dime or ten cents on the register.

I will now explain the automatic connections between the coin-transferring mecha-

nism and the register by which each coin passed into the machine is correctly indicated on the register, *p*, it being understood that each coin actuated plunger stem *c*¹⁰ 5 sets in operation a different train of operating mechanism for properly shifting the register by means of independently movable levers *r'* *r*²⁰ and *r*²⁰ which are respectively actuated by pin and slot connections with 10 said respective plunger stems as shown in Figs. 1 and 14.

Referring first to the mechanism for actuating the register when a nickel is deposited. On the rear face of the wall *a*²⁰ 15 is a rearwardly extending flange, plate or rib *a*²¹, in which is mounted a rock shaft *r* having secured at one end an actuating lever *r'* and at the other end an arm or lever *r*² in the form of a sector gear, which 20 intermeshes with a pinion *r*³ loosely mounted on a hollow arbor *r*⁴; said pinion *r*³ carries a spring pressed pawl *r*⁵, which projects into the open end of a hollow drum *r*⁶, which is provided with four equally 25 spaced notches *r*⁷ about its periphery, toward which notches the pawl *r*⁵ is pressed by its spring, as best shown in Figs. 5 and 6. The pawl *r*⁵ is intended to act as a ratchet against the notches *r*⁷ so as to positively rotate the drum *r*⁶ when the pinion 30 *r*⁴ is moved in a clock-wise direction (Fig. 5), and to ride over the notches when the pinion *r*⁴ is rotated in a contra-clock-wise direction. A safety catch *r*⁹, mounted out- 35 side of the drum serves to yieldingly engage the notches *r*⁷ so as to hold the drum *r*⁶ at rest in proper resting position. It serves the purpose of a safety detent to prevent the drum from frictionally assuming 40 an incorrect position by reason of the frictional pressure of the pawl *r*⁵ during its rotation.

The hollow drum *r*⁶ is secured to the arbor *r*⁴ on the end of which is a ratchet wheel *r*¹⁰ 45 engaging a ratchet pawl *r*¹¹, which is pivotally mounted on the pinion *r*¹² which idles on the hollow arbor *r*⁴, which leads to and actuates the register *p*. Pinion *r*¹² meshes with a pinion *r*¹³ on a counter-shaft which 50 carries a train of gearing *r*¹⁴. This train of gearing actuates the numbering register or counter (Figs. 12 and 18) according to the extent of rotation of the ratchet wheel *r*¹². The nickel actuated registering mechanism 55 already described, is so proportioned that the movement of the cross head *c* acts to rotate the drum *r*⁶ one-quarter turn, corresponding, for example, to five teeth of the ratchet wheel *r*¹² which has twenty teeth in 60 all. This movement produces just one-half revolution of the right-hand disk of the counter equal to five sub-divisions thereof so as to register five cents.

To prevent accidental dislocation of the 65 mechanism from proper registering position

I form the face of the pinion *r*¹³ with a circular series of 10 recesses or apertures *r*¹⁵ adapted to receive a locking bolt *r*¹⁶ which is normally held out of engagement by a tension spring *r*¹⁷ but which is forced into locking engagement with said pinion *r*¹³ by means of a cam block or collar *r*¹⁸ located on the upper tie bar *c*² of the main cross head as illustrated in Fig. 15 so that on the return or forward movement of the main actuating 70 cross head the lock bolt is forced into locking engagement to prevent accidental rotation of the register controlling mechanism. The engaging end of the bolt *r*¹⁶ is preferably tapered to facilitate such locking engagement.

The mechanism for registering a dime is similar to that already described for registering a nickel except that the parts are so proportioned as to cause a half revolution of 85 the drum *r*⁶ instead of a quarter revolution, so as to impart a half revolution equal to ten teeth of the ratchet wheel *r*¹². The dime actuated mechanism embraces a lever *r*²⁰ pivoted in the support *a*²¹ intermediate of its 90 ends and terminating in a sector gear *r*²¹ which engages a pinion *r*²² on which is mounted a pivotal pawl *r*²³ to engage the transverse notches *r*⁷ in the periphery of 95 the drum *r*⁶.

The mechanism actuated by the penny acts directly on the central arbor or shaft *r*³⁰ on the driven end of which is secured a small pinion *r*³¹ actuated by a lever or arm *r*³² carrying a short sector gear *r*³³. At the 100 opposite end of the solid arbor gear *r*³⁰ is secured a ratchet wheel *r*³⁴ adapted to engage a pawl *r*³⁵ mounted on the wheel or pinion *r*¹² which operates the register through engagement with the pinion *r*¹³. 105 The parts in this train of mechanism are so proportioned that on each complete traverse of the cross head the pinion or wheel *r*¹² is rotated one tooth, thereby turning the units disk of the register one degree or step 110 corresponding to one cent. As thus far described the entire handling of the coin and actuating of the mechanism for the normal operation of the machine is accomplished by automatically-operated mechanism controlled or set in motion by the circuit closing action of the coin but it will be perceived as the last coin deposited will remain in the 115 hopper *a*⁵ resting upon the slide *d*. In order to empty the hopper and transfer the coin to its proper destination I have made provision for closing the circuit manually by means of a circuit-closing plunger or rod *s* which, upon being pressed by the conductor, closes the circuit between the terminals *t* *t'*, thus 120 having the same effect as when the same circuit is closed through the automatic-circuit closing members *b* *b'*.

It will be understood that any convenient arrangement of electric wiring for the cir- 130

cuits may be adopted. I have shown, however, in Fig. 9 the removable top or head of the machine provided with two contact pins t t' which fit into corresponding sockets in 5 the top of the main body or casing of the machine, which sockets are insulated from each other and are electrically connected with the coil of the relay electromagnet α as indicated in Fig. 22. When the body or hopper is 10 fastened in place above the casing, the terminal pins t t' are electrically connected, respectively, with the interrupted terminals b b' to form an electrical connection through said sockets with the electromagnet α .

15 It will be seen then that the device comprises, generally speaking, a receiving hopper into which various denominations of coin are to be thrown, suitable selective transferring coin mechanism operatively 20 connected with the adding register by different trains of mechanism actuated through the agency of the individual coin transfer, and a feed device for feeding the coins, one by one, from the hopper to the 25 selective transfer mechanism from which the adding register is appropriately actuated and the preliminary feeding device and the preliminary feed device are automatically set in operation through the medium of the coins deposited.

30 The operation is as follows: The coins thrown into the hopper pass between the terminals b b' into the bottom of the hopper above the slide d , each coin remaining exposed to inspection through the glass sides 35 of the hopper or case until the next coin dropped in closes the circuit between the terminals b b' , thereby causing the slide d to feed a single coin into the body of the selective chute in which are mounted the graduated ledges e , e' , e'' . The coin resting on either pair of ledges again closes the circuit of the relay magnet α by whose agency the solenoid circuit is energized to actuate the 40 plunger and the coin transfer cross head co-operating mechanism. If any coin deposited is too large to pass through the selective orifice adjacent to its actuating plunger it is held on the front edge of said orifice, there- 45 by blocking the further rearward movement of its push rod or plunger while the solenoid plunger continues its descent which is permitted by the yielding operative connection between said plunger and the cross head. The plunger thus continues its downward stroke, opens the circuit-closing switch, previously closed by the relay magnet, and is then returned upward to normal position 50 by means of its tension spring. On this re- 55 turn movement the coin to be excluded is disengaged from the pressure of the push rod forcing it against the edge of the selective orifice and drops in front of the partition outside of the coin storage receptacle.

60 As the cross head has been prevented from

making its complete stroke its movement is insufficient to register through the trains of mechanism leading to the adding register.

If, however, the coin is of the proper size to pass through the selective orifice the main 70 actuating cross head is moved to its full extent, thereby conducting the coin behind the perforated partition from which it passes to its storage receptacle. In this case the full traverse of the plunger cross head being permitted the appropriate train of mechanism 75 leading to the adding register is actuated on the return stroke to give said register the proper amount of rotation.

From a consideration of the above-described mechanism, it will be seen that complete provision has been made for excluding coins of larger diameter or of larger thickness than the largest coin to be accepted by the machine through the medium of the 80 width gaging spider a' and the thickness gaging remove slide d . Furthermore, the clogging of the machine by any irregular sized coins below the size of the largest acceptable coin is completely prevented, while 85 perfect provision is made for the separation of such irregular or intermediate sized coins without operating the registering mechanism. The machine is automatic throughout its normal operation, requires no selection on the part of the passenger depositing the fare since all coins are dropped into a common hopper or receptacle, and requires no manipulation on the part of the conductor except in the single emergency when 90 a disk of less diameter than a nickel but of greater thickness, retains the coin-feeding slide against action until the conductor opens the trap door below the slide, to allow such irregular sized disk to drop down into the casing outside of the selective coin chute. Coins of irregular or unacceptable size that 95 are not excluded by the gaging slide and the gaging spider are handled by the machine automatically without clogging or injuring the machine, while coins of acceptable size, in this case, dimes, nickels and pennies, are distributed to their appropriate pockets and are duly registered by the registering 100 mechanism after such distribution since the registering mechanism operates only on the return movement of the solenoid plunger and cross-head. Except for the removal of 105 too thick a coin after once admitted, the mechanism is entirely out of the control of 110 the conductor or fare depositor, and is completely controlled by the coins admitted to 115 the machine.

Moreover, with this arrangement a handful of nickels, dimes and pennies intermingled with coins of both larger and smaller sizes and of intervening sizes might be dropped on top of the gaging spider at once and every coin would be automatically disposed of by the machine, the regular or 120

acceptable sizes being distributed to their appropriate pockets, while the irregular or unacceptable sizes would be either excluded from entering the hopper, or would be automatically removed from the selective chute without registering on the counter.

What I claim is:

1. In an automatic fare box the combination with a coin-receiving hopper, of a coin feeding-out device for removing the coins singly from said hopper, selective coin-transferring devices by which the coins removed from the hopper are conducted to their respective places of storage, both the 15 coin feeding-out device and the coin-transferring devices being automatically set in operation by the agency of a deposited coin before said coin enters the hopper and being again set in operation by the agency of 20 a coin after it has been removed from said hopper, substantially as described.

2. An automatic fare box embracing in its construction a coin receiving hopper, a coin feeding device for removing the coins 25 singly from said hopper, selective coin transferring devices by which the coins removed from the hopper are conducted to a place of storage, both the coin feeding device and the coin transferring devices being automatically 30 set in operation through the agency of the coins, an adding register operatively connected with said coin transferring mechanism to register the value of the coins after they have been transferred 35 by said mechanism.

3. An automatic fare box embracing in combination a coin-receiving hopper, a selective chute, means for automatically feeding coins one at a time from said hopper to 40 said chute, transferring devices for removing coins of various size from the chute to their appropriate places of storage through different passages, electrically operative means set in operation by the agency of the 45 coin after the coin has been automatically removed from the hopper, substantially as described.

4. An automatic fare box embracing in its construction a coin receiving hopper, a 50 selective coin chute, means for automatically feeding the coins singly from the hopper to said chute, transferring devices for moving various sizes of coins from the chute to their place of storage through different passages, 55 electrically operated means set in operation by the agency of the coin for actuating said feeding and transferring devices, and an adding register operatively connected with said coin transferring mechanism to register 60 the value of the coins after they have been transferred.

5. An automatic fare box embracing in combination a casing including a coin-receiving hopper constructed to permit inspection of coins in the bottom thereof, a selec-

tive coin chute and a storage receptacle, means for automatically feeding the coins out of the hopper into the chute and means for transferring the coins from the chute to the storage receptacle, an electrically 70 actuated coin-retaining detent arranged to temporarily prevent the deposited coin from entering said hopper, said detent being released automatically through electrically operated means which actuate the coin-feeding and the coin-transferring devices, substantially as described.

6. An automatic fare box embracing in its construction a coin-transferring device, a receiving hopper, a selective coin chute 80 and a coin-carrying slide for feeding the coin from the hopper to said chute said slide being actuated by means of a solenoid whose controlling circuit is closed through the electrical contact of the coin with its separated 85 terminals before the coin enters said hopper, and a supplemental controlling circuit whose separate terminals are closed by electrical contact with the coin after it is removed from said hopper, substantially as 90 described.

7. In an automatic fare box the combination of a common hopper for receiving coins of different predetermined denominations, provided with a gaging intake for excluding coins of greater diameter than the largest acceptable coin, a coin removing member for removing the coins singly from the hopper to a selective and separating chute, while excluding coins of excessive thickness, 95 and an electrically operated transfer mechanism for transferring the acceptable coins from their appropriate positions in said chute to their appropriate receptacles, said electrically operated mechanism being automatically energized by the coins, substantially 100 as described.

8. The combination of a coin receiving hopper, a coin containing carrier located at the bottom of said hopper in position to 110 support a coin there, means for actuating said carrier to remove the coin from the hopper, a pair of coöperating members arranged to momentarily engage and support the coin in said hopper, said coin engaging 115 members forming separate terminals of an electric circuit that is closed by the interposed coin to cause the actuating mechanism to operate said carrier and to move one of the engaging members from supporting contact with the coin to allow the coin to fall upon said carrier.

9. In a coin box the combination with a coin receptacle, of a coin chute, a partition separating said chute from the coin receptacle, and provided with a selective aperture, and electrically operated means for transferring the coin from the chute through the aperture on said partition, said electrically operated means being actuated 125 130

by an electric current that is energized through the agency of the deposited coin, substantially as described.

10. In an automatic coin box the combination of a hopper for receiving coins of different denominations, a coin removing member automatically operated by a coin entering the hopper to remove a coin from the hopper to a coin selective chute, a vertically arranged series of pairs of oppositely spaced coin supporting members forming electrical terminals which are closed by the coin resting thereon, a coin transferring and gaging mechanism arranged to remove a 15 coin resting on any pair of contact members and transfer it to its appropriate receptacle, said transferring mechanism being automatically operated through the agency of an electric circuit passing through said 20 terminals, substantially as described.

11. In a fare box the combination of a common coin receiving hopper for coins of predetermined denominations, a coin removing member for removing coins singly from 25 said hopper to a coin selective chute, coin transferring mechanism for transferring different denominations of coin from said selective chute to their appropriate receptacles, electrically operated means set in action 30 by the deposited coin for operating said transferring mechanism and said coin removing mechanism, and a registering mechanism automatically operated by the return movement of said coin transferring mechanism, substantially as described.

12. In a fare box the combination of a coin receiving hopper for coins of different denominations, means for removing coins from said hopper to a selective chute, coin 40 transferring gaging mechanism for removing coins of acceptable size from said coin chute to their appropriate coin pockets and for removing from said chute and excluding from said pockets coins of unacceptable 45 size, a registering mechanism operated by the coin transferring mechanism after it has transferred any acceptable coin to its appropriate receptacle, substantially as described.

50 13. In fare boxes the combination with a selective coin separating coin chute, a series of transferring devices arranged to transfer coins from their appropriate location in said coin chute to appropriate receptacles, a coin 55 receiving hopper for different denominations of coins, a coin removing member operatively connected with said coin transferring mechanism and arranged to remove the coin from the receptacle on the return movement of said coin transferring mechanism, substantially as described.

60 14. In a fare box the combination of an interior selective coin chute, a plurality of selective coin transfer devices appropriate 65 to different denominations of coin, actuating

mechanism for said coin transfer devices constructed to be set in operation by the agency of the appropriate coin in said coin chute, said actuating mechanism being operatively connected with said coin transferring mechanism by the interconnecting devices normally acting to transmit motion from said actuating mechanism to said transfer mechanism, said connection being operatively interrupted to permit movement of the actuating mechanism when a coin of improper size blocks the movement of the transferring mechanism, substantially as described. 70 75

15. In a fare box the combination of a selective coin chute or passage, coin transferring mechanism for moving different denominations of coin through said chute, a solenoid plunger operatively connected with said transferring mechanism to actuate the 80 same through the agency of a deposited coin, and means permitting the release of the operative connection between the solenoid and the transferring mechanism when the movement of the transferring mechanism is blocked by a coin of improper size. 90

16. In a fare box the combination of a selective coin chute, a reciprocatory frame provided with a series of push rods to engage different sizes of different coins in different locations in said chute, a series of corresponding co-acting plungers passing through the selective orifices to engage and assist in transferring the respective coins, an electrically actuated plunger, a pivoted arm 100 forming an operative connection between said plunger and the coin transferring mechanism, said arm being operatively interconnected with the coin transferring devices by an operative connection which allows said arm to be moved by the plunger when the movement of the coin transferring devices is obstructed, substantially as described. 95 105

17. In a fare box the combination of a coin chute, coin transferring mechanism for transferring coins of various sizes to a storage receptacle, an electrically operated actuating member operatively connected with said coin transferring mechanism, means for returning said actuating member to normal 110 position when its operating circuit is broken, and a retarding device for retarding the return movement of said actuating member in order to give time to release the coin from the transferring mechanism, substantially as 115 described. 120

18. In a fare box the combination of a coin transferring mechanism embracing positively actuated and separate idle members which between the coin transferred is 125 pinched, a solenoid actuated plunger operatively connected with the positively actuated members of said coin transferring mechanism, means for deenergizing said solenoid when said plunger has completed 130

its traverse, a tension spring for returning said solenoid plunger to normal position, and a speed retarding mechanism for delaying the initial return movement of said plunger, substantially as described.

19. In a fare box the combination of a hopper for receiving coins of different denomination, a movable coin containing carrier for feeding coins from said hopper to a selective coin chute for distribution, said coin slide being normally out of position to receive the coin in the hopper, an actuating mechanism for moving said carrier into coin receiving position and for returning said carrier to its normal position whence it delivers the coin to said coin chute, substantially as described.

20. In a fare box the combination of a coin chute, of a series of coin transferring devices for coins of different denominations, an adding register, and independent trains of connecting mechanism for operatively connecting each individual coin transferring device on its return stroke with said register in order to register and add the value of the different coins transferred, substantially as described.

21. In a fare box the combination of a plurality of coin transferring devices for transferring coins of different denominations to a storage receptacle, a series of independently mounted levers engaged by the respective coin transferring devices, an adding register, and differential trains of gearing interconnecting the respective levers with said register to operate said register according to the value of the respective coins transferred on the return stroke of said transfer mechanism, substantially as described.

22. In a fare box the combination of an adding register provided with a driving pinion, a series of actuating levers each of which is operatively connected with said driving pinion by a pawl-carrying wheel, a series of differentially actuated ratchet wheels operatively connected with said ac-

tuating levers to rotate said pawl-carrying wheel through different arcs of its circumference in order to secure a differential rotation of said register, substantially as described.

23. In a fare box the combination of a selective coin chute and coöperating coin transferring devices, of a receiving hopper, a coin delivering device for delivering the said coins from said hopper to said feed chute one at a time actuated by a coin controlled electric circuit, and externally operated means for freeing said coin delivering member from a deposited piece of greater thickness than the coins which said member is intended to deliver, substantially as described.

24. In a fare box the combination of an inclosing casing, and inclosed receiving hopper superimposed thereon, a coin containing carrier located at the bottom of the hopper to receive the coins deposited, a pair of coöperating coin engaging members supported above the bottom of said hopper in position to engage each coin dropped therein, said coin engaging members being electrically connected with actuating mechanism to cause said actuating mechanism to operate said coin carrier when a deposited coin is in contact with both engaging members, substantially as described.

25. In a fare box the combination with a coin chute for receiving the coin deposited, automatically-operated selective coin-transferring mechanism, an adding counter, actuating mechanism connecting the coin-transferring mechanism operatively with said counter embracing differentially rotated clutch actuated pinions and means actuated by the transferring mechanism to accurately set and lock the counter actuating mechanism in its different operative positions, substantially as described.

In witness whereof, I have subscribed the above specification.

ERNEST H. THOMPSON.
